Des. 348

Samuel A. House of Mechanicville, N.Y.

Letters Patent No. 348 Dated Feb¹⁴ 1851.

The Schedule referred to in these Letters Patent and making part of the same.

To all to whom it may concern: Weil known, that I, Samuel A. House of Mechanicville, in the County of Saratoga and State of New York, have invented or produced a new design of cook stove, and I do hereby declare that the following is a full, clear and exact description of the same, reference being had to the annexed drawings, making a part of this specification, in which fig. 1 is a side elevation, and fig. 2 a view of the front plate of the stove.

The ornamental design of my stove consists of arabesque figures disposed on the panels of the side doors and other parts of the stove, as represented, and in the mouldings forming the panels of the doors, and the combination of mouldings &c.

What I claim as new and desire to secure by Letters Patent, is the design of cook stove, substantially the same as herein described and represented.
